SLIDE FASTENER

Ralph E. Jones, San Diego, Calif.

Application May 19, 1958, Serial No. 736,094

1 Claim. (Cl. 24—205.15)

The present invention relates in general to slide fasteners and, more particularly, to a device for preventing jamming of such a fastener due to entanglement of fabric with the fastening elements thereof, or between the fastening elements and the slider thereof, the present invention being an improvement on that of my copending patent application Serial No. 548,930, filed November 25, 1955, now Patent No. 2,855,652, issued October 14, 1958.

Before proceeding to a consideration of the present invention, a conventional slide fastener with which the invention is utilized will be described briefly, primarily for the purpose of establishing basic terminology to be utilized throughout the present application. The slide fastener with which the invention is associated has interior and exterior sides which, in the case of a slide fastener mounted on a garment, respectively face toward and away from the body of the wearer of the garment. Occasionally, the interior side of the slide fastener will be referred to herein as the "undergarment" side thereof. The slide fastener includes two tapes respectively carrying two interengageable rows of fastening elements, each of these rows defining interior and exterior surfaces spaced from and paralleling the corresponding tape and respectively located on the interior and exterior sides of the slide fastener. Finally, the slide fastener includes a slider or slider means movable along and engageable with the rows of fastening elements for interengaging and disengaging same to close and open the slide fastener, depending on whether the slider is moved in a slide-fastener closing direction, or a slide-fastener opening direction. The direction of slide-fastener closing movement of the slider will be regarded herein as the forward direction, and the direction of slide-fastener opening movement of the slider will be regarded as the rearward direction.

A primary object of the invention is to take advantage of the fact that the aforementioned interior and exterior surfaces of the rows of fastening elements act as interior and exterior platforms which hold extraneous fabric away from the interior and exterior sides, respectively, of the tapes.

More particularly, the primary object of the invention is to provide a jam preventing device which includes prongs having ends disposed laterally outwardly of, but in close proximity to, the rows of fastening elements and disposed between the interior and exterior surfaces of the rows of fastening elements.

With the foregoing construction, the prong ends ride on the tapes and are inserted between the tapes and any extraneous fabric which must be displaced out of the path of the slider, there being no possibility with this construction of entangling such extraneous fabric between the fastening elements and the slider, or between the fastening elements and the prongs themselves.

An important object of the invention is to provide a jam preventing device which includes a team of three in-

2

terior closing prongs carried by the slider on the interior side of the slide fastener and extending forwardly from the slider in the direction of slide-fastener closing movement of the slider, as disclosed in my aforementioned copending application. This team of interior closing prongs includes two outer interior closing prongs having forward ends respectively disposed laterally outwardly of the rows of fastening elements and respectively disposed between the interior and exterior surfaces of the rows of fastening elements, and includes an intermediate interior closing prong disposed between the rows of fastening elements and spaced from the outer interior closing prongs distances greater than the widths of the rows of fastening elements and having a forward end disposed between the interior and exterior surfaces of the rows of fastening elements. With this construction, the outer interior closing prongs serve to move any extraneous fabric away from the interior surfaces of the rows of fastening elements during slide-fastener closing movement of the slider, and the intermediate interior closing prong displaces any extraneous fabric which may be between the two rows of fastening elements during slide-fastener closing movement of the slider. This teamwork between the three interior closing prongs insures against jamming on the interior or undergarment side of the slide fastener during closing movement of the slider.

Another important object of the invention is to provide a jam preventing device which includes two exterior closing prongs carried by the slider on the exterior side of the slide fastener and extending forwardly from the slider in the direction of slide-fastener closing movement of the slider, such exterior closing prongs having forward ends respectively disposed laterally outwardly of the rows of fastening elements and respectively disposed between the interior and exterior surfaces of the rows of fastening elements. These exterior closing prongs serve to move out of the way any extraneous fabric on the exterior side of the slide fastener during closing movement of the slider. In this case, no intermediate prong is necessary since any extraneous fabric which is not displaced during closing movement by the intermediate interior closing prong is displaced by the usual operating tab attached to the slider, which tab extends forwardly in the direction of closing movement during such movement of the slider.

An important object of the invention is to stagger the forward ends of the outer interior closing prongs relative to the forward ends of the exterior closing prongs in the direction of movement of the slider so that the forward ends of these prongs do not pinch the tapes therebetween. A related object is to locate the forward ends of the exterior closing prongs closer to the slider than the forward ends of the outer interior closing prongs.

Another object is to provide a jam preventing device which includes, in conjunction with the three interior closing prongs and the two exterior closing prongs hereinbefore discussed, two interior and two exterior opening prongs each having a rearward end disposed laterally outwardly of the corresponding row of fastening elements and disposed between the interior and exterior surfaces of such row of fastening elements. Another object is to stagger the rearward ends of the exterior opening prongs relative to the rearward ends of the interior opening prongs, the rearward ends of the exterior opening prongs preferably being closer to the slider than the rearward ends of the interior opening prongs.

The rearward ends of the interior and exterior opening prongs cooperate with the interior and exterior surfaces of the tapes and the interior and exterior surfaces of the rows of fastening elements to move out of the way any extraneous fabric which may tend to jam between the

slider and the rows of fastening elements during slide-fastener opening movement of the slider, in much the same way that the forward ends of the outer interior closing prongs and the exterior closing prongs prevent jamming during slide-fastener closing movement of the slider.

Another object is to provide a jam preventing device wherein the intermediate and outer interior closing prongs are arcuate and curve toward positions between the interior and exterior surfaces of the rows of fastening elements at the forward ends thereof so as to lift any extraneous fabric on the undergarment side of the slide fastener well away from the slider to insure jam prevention during closing movement of the slider.

The foregoing objects, advantages, features and results of the present invention, together with various other objects, advantages, features and results thereof which will be evident to those skilled in the slide fastener art in the light of this disclosure, may be attained with the exemplary embodiment of the invention described in detail hereinafter and illustrated in the accompanying drawing, in which:

Fig. 1 is a view partially in section and partially in elevation of a slide fastener which embodies the jam preventing device of the present invention;

Fig. 2 is a plan view of the exterior side of the slide fastener and jam preventing device; and

Fig. 3 is a plan view of the interior side of the slide fastener and jam preventing device.

In the drawing, the number 10 designates generally a slide fastener having an interior or undergarment side 12 and an exterior side 14. The slide fastener 10 includes two tapes 16 respectively carrying two interengageable rows 18 of fastening elements 20, the rows 18 having interior and exterior surfaces 22 and 24 respectively disposed on the interior and exterior sides 12 and 14 of the slide fastener and respectively spaced from and paralleling the tapes 16. The slide fastener 10 also includes a slider or slider means 26 movable along and engageable with the rows 18 of fastening elements 20 for interengaging and disengaging same to close and open the slide fastener in response to slide-fastener closing and opening movements, respectively, of the slider 26, as is well known in the art, the direction of slide-fastener closing movement being toward the right, as viewed in the drawing, and the direction of slide-fastener opening movement being toward the left, as viewed therein. A manually graspable tab 28 is pivotally connected to the slide 26 on the exterior side 14 thereof in the usual manner.

The jam preventing device of the invention includes two outer interior closing prongs 30 and one intermediate interior closing prong 32 carried by the slider 26 on the interior side 12 of the slide fastener 10 and extending forwardly from the slider in the direction of slide-fastener closing movement of the slider. The outer interior closing prongs 30 curve forwardly to forward ends 34 respectively disposed laterally outwardly of, but in close proximity to, the rows 18 of fastening elements 20 and respectively disposed between the interior and exterior surfaces 22 and 24 of the rows 18 in engagement with the tapes 16, as best shown in Fig. 1 of the drawing. The intermediate interior closing prong 32 (also) curves toward a forward end 36 which is disposed between the interior and exterior surfaces 22 and 24 of the rows 18, and which is disposed between the rows, the intermediate interior closing prong 32 being spaced laterally from the outer interior closing prongs 30 distances greater than the widths of the rows 18 of fastening elements 20 so that extraneous fabric cannot become caught between such prongs and the fastening elements.

It is thought that the operation of the interior closing prongs 30 and 32 will be clear from Fig. 1 of the drawing, which shows fabric 38 in contact with the slide fastener 10 on the interior or undergarment side 12 thereof, and fabric 38 being shown as having a fold 40 which pro-

jects outwardly between the disengaged portions of the rows 18 to the exterior side 14 of the slide fastener. Note that the fabric 38 is held away from the tapes 16 by the interior surfaces 22 of the rows 18 so that the forward ends 34 of the outer interior closing prongs 30, being in engagement with the interior sides of the tapes 16, are inserted between the tapes and the fabric to displace the fabric out of engagement with the fastening elements during slide-fastener closing movement of the slider 26, thereby eliminating any possibility of jamming of the fabric 38 between the outer interior closing prongs 30 and the rows 18 of fastening elements 20, or jamming of the fabric between the rows of fastening elements and the slider. Note also that the intermediate interior closing prong 32 disposed between the disengaged portions of the rows 18 of fastening elements 20 effectively displaces the fold 40 cut from between the disengaged portions of the rows 18 to the interior side 12 of the slide fastener 10 during slide-fastener closing movement of the slider 26.

Thus, the three interior closing prongs 30 and 32 work as a team to prevent jamming of the fabric 38 with respect to all parts of the device.

The jam preventing device of the invention also includes two exterior closing prongs 42 carried by the slider 26 on the exterior side 14 of the slide fastener 10 and extending forwardly from the slider in the direction of slide-fastener closing movement thereof, the exterior closing prongs 42 curving toward forward ends 44 thereof respectively disposed laterally outwardly of the rows 18 of fastening elements 20 and respectively disposed between the interior and exterior surfaces 22 and 24 of such rows. The forward ends 44 of the exterior closing prongs 42 are in engagement with the tapes 16, respectively, and are staggered in the direction of slider movement relative to the forward ends 34 of the outer interior closing prongs 30 so as to avoid pinching the tapes 16 between the forward ends 34 and the forward ends 44, the forward ends 44 preferably being located closer to the slider 26 than the forward ends 34.

The exterior closing prongs 42 operate with respect to extraneous fabric in substantially the same way as the outer interior closing prongs 30 operate with respect thereto during slide-fastener closing movement of the slider 26. In this case, the extraneous fabric may comprise the edges of a garment which overlie the rows 18 of fastening elements 20 to conceal the fastener 10 when it is closed.

The jam preventing device of the invention also provides two interior opening prongs 46 and two exterior opening prongs 48 respectively carried by the slider 26 on the interior and exterior sides 12 and 14 of the slide fastener 10 and extending rearwardly from the slider 26 in the direction of slide-fastener opening movement of the slider. The interior opening prongs 46 curve rearwardly to rearward ends 50 respectively disposed laterally outwardly of the rows 18 of fastening elements 20 and respectively disposed between the interior and exterior surfaces 22 and 24 thereof. Similarly, the exterior opening prongs 48 curve rearwardly to rearward ends 52 respectively disposed laterally outwardly of the rows 18 of fastening elements 20 and respectively disposed between the interior and exterior surfaces 22 and 24 of the rows. The rearward ends 50 and 52 respectively engage the interior and exterior surfaces of the tapes 16 and, in order to avoid pinching of the tapes, the rearward ends 50 are staggered relative to the rearward ends 52 in the direction of slider movement, the rearward ends 52 of the exterior opening prongs 48 preferably being closer to the slider.

During slide-fastener opening movement of the slider 26, the interior opening prongs 46 operate with respect to extraneous fabric, such as the fabric 38, in much the same manner as the outer interior closing prongs 30 do during closing movement. Similarly, the exterior opening prongs 48 operate with respect to extraneous fabric during open-

ing movement in much the same manner as the exterior closing prongs 42 do during closing movement.

The net result of providing a jam preventing device having five prongs operative during closing movement and four prongs operative during opening movement is to completely insure against jamming under all conditions of operation, which is an important feature.

Although an exemplary embodiment of the invention has been disclosed herein for purposes of illustration, it will be understood that various minor changes, modifications and substitutions may be incorporated in such embodiment without departing from the spirit of the invention as defined by the claim which follows:

I claim:

A jam preventing device for a slide fastener which has 1
interior and exterior sides and which includes two tapes, 2
two interengageable rows of fastening elements respectively 20
carried by the tapes and respectively defining interior and exterior surfaces spaced from and paralleling 25
the tapes, and slider means movable along and engageable 30
with the rows of fastening elements for interengaging same to close the slide fastener, said device including: two outer interior closing prongs carried by the slider means on the interior side of the slide fastener and extending forwardly from the slider means in the direction of slide-fastener closing movement of the slider means, said outer interior closing prongs having forward ends respectively disposed laterally outwardly of the rows of fastening elements and respectively disposed between the interior and exterior surfaces of the rows of fastening elements; an intermediate interior closing prong carried by the slider means on the interior side of the slide fastener and extending forwardly from the slider means in the direction of slide-fastener closing movement of the slider means, said intermediate interior closing prong being disposed between the rows of fastening elements and being spaced from said outer interior closing prongs distances greater than the widths of the rows of 35

fastening elements and having a forward end disposed between the interior and exterior surfaces of the rows of fastening elements; two exterior closing prongs carried by the slider means on the exterior side of the slide fastener and extending forwardly from the slider means in the direction of slide-fastener closing movement of the slider means, said exterior closing prongs having forward ends respectively disposed laterally outwardly of the rows of fastening elements and respectively disposed between the interior and exterior surfaces of the rows of fastening elements; two interior opening prongs carried by the slider means on the interior side of the slide fastener and extending rearwardly from the slider means in the direction of slide-fastener opening movement of the slider means, said interior opening prongs having rearward ends respectively disposed laterally outwardly of the rows of fastening elements and respectively disposed between the interior and exterior surfaces of the rows of fastening elements; and two exterior opening prongs carried by the slider means on the exterior side of the slide fastener and extending rearwardly from the slider means in the direction of slide-fastener opening movement of the slider means, said exterior opening prongs having rearward ends respectively disposed laterally outwardly of the rows of fastening elements and respectively disposed between the interior and exterior surfaces of the rows of fastening elements; said forward ends of said exterior closing prongs being located closer to the slider means than said forward ends of said outer interior closing prongs, and said rearward ends of said exterior opening prongs being located closer to the slider means than said rearward ends of said interior opening prongs.
